UNITED STATES PATENT OFFICE.

EDWARD D. VARNUM, OF SAN DIEGO, CALIFORNIA, ASSIGNOR TO VARNUM CRUDE OIL BURNER CO., OF SAN DIEGO, CALIFORNIA, A CORPORATION OF CALIFORNIA.

OIL-BURNER.

1,179,781.

Specification of Letters Patent. Patented Apr. 18, 1916.

Application filed May 10, 1915. Serial No. 26,979.

To all whom it may concern:

Be it known that I, EDWARD D. VARNUM, a citizen of the United States, residing at San Diego, in the county of San Diego and 5 State of California, have invented certain new and useful Improvements in Oil-Burners, of which the following is a specification.

My invention relates to oil burners in which oil and water are mixed for use as a 10 fuel more particularly crude oil or distillate.

The objects of my invention are, first and primarily, improvements in crude oil burners, over my application of January 4, 1915, Serial Number 334, principally to make the 15 burner more efficient and durable and to render its feed portion less liable to clog.

With these and other objects in view as will appear hereinafter my invention consists of certain novel features of construction, combination and arrangement of parts 20 as will hereinafter be described in detail and particularly set forth in the appended claims, reference being had to the accompanying drawings and to the characters of 25 reference thereon which form a part of this specification, in which:

Figure 1, of the drawing shows a sectional view of my burner complete, and Fig. 2, a top view of the oil feed cone.

30 The burner plate 1, feed cone 2, water feed pipe 3, hood and oil conductor 4, fuel feed piece 5, flame control 6, oil pipe 7, air intake 8, support 9, hood 10 and main hood 11, constitute the principal parts of my burner.

35 The air intake 8 is a bell shaped casting open at the top end and it is provided with lugs 8^a for supporting it on the support 9. Upon the top edge of this air intake piece 8, is mounted the burner plate 1, which is provided with a hole 1^a and a shoulder 1^b to set 40 over the top and when pressed down forms a tight fit thereon, the shoulder 1^b preventing the oil from running toward the center of the burner plate 1. The support 9 is a

45 spider with extended arms 9^a and it is screwed onto the water feed pipe 3, which is in two parts and connected together by said support. Inside this water pipe 3, is mounted the oil pipe 7 which is a smaller pipe. 50 Upon the upper end of this oil pipe 7 is screwed the fuel feed piece 5 which is provided with a partition 5^a and with a recess in its upper and lower ends and the upper end is provided with a plurality of holes 5^b for oil feed and in the lower end thereof 55

with a plurality of holes 5^c for the water feed. This feed piece is threaded and screws into the end of the feed cone 2 which is threaded in its lower end adapted to screw on to the top end of the water pipe 3. This cone 2 is provided with a plurality of slots 2^a therein extending from its apex to near the outer edge and each slot is provided with a pipe 2^b for conducting the fuel to the burner plate 1. The outer edge is provided with a projection 2^c, adapted for the flame guide ring 6, which is a ring of approximately the same diameter as the burner plate 1. Over this cone 2 and screwed on the feed piece 5, is the hood and oil conductor 4, which fits closely to the cone allowing the water to run down over the cone beneath said hood and through the pipes 2^b to the burner plate 1. Some distance from the center thereof, and on the top end of the 70 feed piece 5 is the hood 10 which extends down over the hood and oil conductor 4, some distance and mounted on the plate 6 and covering the feed parts is the main hood 11.

It is obvious that with this construction there is provided an oil burner for burning a mixture of oil and water in which the oil and water are thoroughly distributed upon a plate upon which the mixture is burned; that the two plates, 1 and 6, spaced apart provide means for guiding the flame; that the feed piece 5, provides means for separately distributing the oil and water which are kept separate by means of the hood and oil conductor 4 but finally uniting toward the outer edge of the feed cone 2 and then conducted to the plate 1 where it is burned between the plates 1 and 6, the draft coming up through the piece 8.

Having thus described my invention what I claim as new and desire to secure by Letters Patent, is:

1. In an oil burner, the combination of an air intake piece, water and oil feed pipes 100 extending up through said air intake piece, a burner plate mounted on said air intake piece, a cone for distributing oil and water onto said burner plate, and means for separately conducting the oil and water to said 105 cone.

2. In an oil burner, the combination of an air intake piece, a burner plate mounted thereon, water and oil pipes extending up through said air intake piece, a cone pro- 110

2
vided with means in its periphery for distributing oil and water on said burner plate, means for separately conducting water and oil to said cone, another plate spaced apart 5 above said burner plate, and a hood covering the central part of said plate, said cone, and separating means.

3. In an oil burner the combination of an air intake piece, a burner plate mounted thereon, water and oil pipes extending up through said air intake piece, means mounted on the upper end of said water and oil pipes for distributing water and oil onto said burner plate, and another plate spaced 15 apart above said burner plate.

4. In an oil burner the combination of an air intake piece, a burner plate mounted thereon, water and oil pipes extending up through said air intake piece, a cone provided with a plurality of grooves in its upper surface mounted on the upper end of

the water supply pipe, a feed piece mounted in the upper end of said cone, and means for keeping the oil and water separate during a portion of its course to the burner 25 plate.

5. In an oil burner the combination of an air intake piece, a burner plate mounted thereon, water and oil pipes extending up through said air intake piece, a cone provided with a plurality of grooves in its upper surface mounted on the upper end of the water supply pipe, a feed piece mounted in the upper end of said cone, means for keeping the oil and water separate during a 30 35 portion of its course to the burner plate, and hood means for covering the feed mechanism.

In testimony whereof, I have hereunto set my hand at San Diego, California, this 23rd 40 day of April, 1915.

EDWARD D. VARNUM.
